UNITED STATES PATENT OFFICE.

JOSEPH G. KAEMPFER, OF NEW YORK, N. Y.

DESIGN FOR A DOLL-FIGURE.

53,915.

Specification for Design.

Patented Oct. 7, 1919.

Application filed May 1, 1919. Serial No. 294,068. Term of patent 7 years.

To all whom it may concern:

Be it known that I, JOSEPH G. KAEMPFER, residing and having my post-office address at #370 Central Park West, in the borough of Manhattan, city, county, and State of New York, and a citizen of the United States, have invented a new, original, and ornamental Design for a Doll-Figure, of which the following is a specification, reference being had to the accompanying drawing, forming part thereof.

The figure shows a front view of the doll, showing my new design.

JOSEPH G. KAEMPFER.
